SAFETY RAZOR BLADE ASSEMBLY

Roger L. Perry, Lynnfield Center, Mass., assignor to The
Gillette Company, Boston, Mass.

Filed Mar. 15, 1971, Ser. No. 124,662

Term of patent 14 years

Int. Cl. D28—03

U.S. Cl. D95—3

Fig. 1

Fig. 2

Fig. 3

Fig. 4

Fig. 5

FIG. 1 is a perspective view of a safety razor blade assembly showing my new design;

FIG. 2 is a top plan view thereof;

FIG. 3 is a bottom plan view thereof;

FIG. 4 is a front elevational view, the rear being substantially the same; and

FIG. 5 is an end elevational view, the opposite end being substantially the same.

I claim:

The ornamental design for a safety razor blade assembly, substantially as shown and described.
